QUILTED PLASTIC FILM MATERIAL
OR THE LIKE

Daniel E. Hogan, Jr., Andover, Mass., assignor to
Bolta Products Sales, Inc., Lawrence, Mass., a
corporation of Massachusetts

Application September 29, 1951, Serial No. 16,786

Term of patent 14 years

(Cl. D87—3)

To all whom it may concern:

Be it known that I, Daniel E. Hogan, Jr., a citizen of the United States and a resident of Andover, county of Essex, Commonwealth of Massachusetts, have invented a new, original, and ornamental Design for Quilted Plastic Film Material or the like, of which the following is a specification, reference being had to the accompanying drawing, forming part thereof.

In the drawing:

Fig. 1 is a plan view of quilted plastic film material or the like, showing my new design;

Fig. 2 is a section on the line 2—2 of Fig. 1 on an enlarged scale; and

Fig. 3 is a section on the line 3—3 of Fig. 1 on an enlarged scale.

I claim:

The ornamental design for quilted plastic film material or the like, substantially as shown.

DANIEL E. HOGAN, JR.
